DESIGN FOR A LIGHTING UNIT

Andrew T. Browne, Lansdowne, Pa.

Application August 10, 1937, Serial No. 70,952

Term of patent 14 years

To all whom it may concern:

Be it known that I, Andrew T. Browne, a citizen of the United States, residing at Lansdowne, Delaware County, State of Pennsylvania, have invented a new, original, and ornamental Design for a Lighting Unit, of which the following is a specification, reference being had to the accompanying drawing, forming part thereof.

Figure 1 is a side elevational view of the lighting unit showing my new design;

Fig. 2 is a bottom plan view of the lighting unit of the present design;

Fig. 3 is a cross-sectional view taken on the line 3—3, Fig. 2, and

Fig. 4 is a fragmentary top plan view of the lighting unit, a portion of the reflector being broken away to show the grille.

I claim:

The ornamental design for a lighting unit, as shown and described.

ANDREW T. BROWNE.
